UNITED STATES PATENT OFFICE.

MONROE GUETT, OF HARTFORD, CONNECTICUT, ASSIGNOR TO THE HART & HEGEMAN MANUFACTURING COMPANY, OF HARTFORD, CONNECTICUT, A CORPORATION OF CONNECTICUT.

LAMP-SOCKET MEMBER.

1,258,559.

Specification of Letters Patent.

Patented Mar. 5, 1918.

Application filed September 26, 1916. Serial No. 122,309.

To all whom it may concern:

Be it known that I, MONROE GUETT, a citizen of the United States, and a resident of Hartford, in the county of Hartford, 5 State of Connecticut, have invented certain new and useful Improvements in Lamp-Socket Members, of which the following is a specification.

The invention has for its object the production of a novel form of socket member to take the base of an incandescent lamp. The ordinarily lamp socket, as that term is commonly used, comprises in the complete structure a screw threaded shell into which 10 the lamp base is screwed and which is connected to one side of the circuit and a stationary contact point, usually located centrally of the end of the socket, with which the contact at the center of the lamp base 15 engages. The socket member forming the subject matter of this invention takes the place of the screw threaded shell ordinarily used. It may be connected up in circuit in any well known manner and may be supported in place in any desired way and 20 either held against motion, or otherwise supported, as for instance in my co-pending application S. No. 160,065.

In the drawings—

30 Figure 1 is a front view of the device forming the subject matter of my invention.

Fig. 2 is an edge view thereof looking from the side of Fig. 1.

Fig. 3 is an edge view looking from the 35 top of Fig. 1.

Fig. 4 shows the manner of use in connection with an incandescent lamp bulb.

Referring to the drawings it will be found that the device forming the subject matter 40 of this invention, and which is generally indicated by A, consists of a spirally formed single convolution of stock, of proper thickness to engage and move in the thread of the complementary member. At the 45 points where the stock is axially displaced to give it a spiral formation, as at a, b, there

is an integral connecting portion c, notched on its inner edge as at d. As will be clearly seen in the drawings, this notch is in the connecting portion c, which is angularly disposed with relation to the general plane of the structure, forming a means for starting the member onto the screw base of a lamp. The pitch of the spiral will of course correspond closely to the pitch of the thread 55 of the base.

The structure is of general annular form, the wall of which is narrow for the most part but is substantially increased in width at the point where the stock is axially displaced to produce the spiral formation, the notch d being formed in the axially displaced portion in order to permit of entering the threads of the lamp base into this socket member. This provides a very compact structure, adapted for use where any present form of lamp socket cannot be used, and thus making it possible to utilize screw base lamps where it has not been heretofore possible to use them. 70

In accordance with the provisions of the patent statutes, I have described the principle of operation of my invention, together with the apparatus which I now consider to represent the best embodiment thereof; but 75 I desire to have it understood that the apparatus shown is only illustrative, and that the invention can be carried out by other means.

I claim as my invention:

80 A lamp socket member formed in the shape of a solid annulus from sheet metal, the wall of which is at one point increased in width and axially displaced to produce a spiral formation of the annulus, and a notch 85 in the inner edge of the axially displaced portion of the wall.

MONROE GUETT.
